INVENTOR

Arthur W. Spaulding.

UNITED STATES PATENT OFFICE.

ARTHUR W. SPAULDING, OF OAKLAND, CALIFORNIA.

MACHINE FOR SEAMLESS CANS.

Application filed July 5, 1927. Serial No. 203,527.

My invention relates to improvements in machinery for the manufacture of cans and the objects of my improvement are to provide means for feeding the wall of a tube between 5 rollers, means for enlarging the tube by rolling, automatic means for changing the angle of the tube in relation to the rollers and so causing its return and discharge.

I accomplish these objects by the means 10 illustrated in the accompanying drawings, in which—

Figure 1 is a perspective of the machine with one guide removed,

Fig. 2 is a perspective view of the tube to be 15 enlarged,

Fig. 3 is a plan view of the guides and their control, and

Fig. 4 is an elevation of the shafts and gears.

20 The metal block 1 acts as a bearing for the main roller 2. The upper roller consists of a heavy sleeve 3 fitted upon the end of a shaft 4. The shaft lies in a housing 5 which is mounted upon the block 1 by means of a 25 hinge 6.

Rising from the block 1 on either side of the housing 5 are bolts 7 supporting a cross-bar 8, in the center of which is an adjusting screw 9 for regulating the pressure between the 30 rollers. On both sides of the sleeve roller 3 are guides 10, bearing small rollers 11. The guides are mounted upon vertical rods 12 which pass downward thru the block 1. By means of set screws 34, bell cranks 13 are 35 attached to the rods 12 below the block 1, and at the opposite ends are connected by a drag rod 14 of right length to keep the bell cranks parallel.

40 A spring 15, coiled upon the pin 16 within a cylinder 17, has a projecting end 18. The spring bears upon a pin 19 in the drag rod 14. The sliding core of the solenoid 20 is attached to one of the bell cranks 13 by the rod 21.

At the side of the block 1 is mounted a sliding rod 22, provided at one end with a hook 45 23, at the other with an electric contact 24, and in the middle with a sliding stop 25 having a horizontal arm 26.

To the side of block 1 is rotatably attached 50 the vertical arm 27 of a horizontal lever 28. A balancing weight 29 is adjustably attached to one end of the lever. Electric wires 30 run from the sliding switch 24 to the solenoid 20. At the rear of the upper roller 4 is the gear 55 wheel 31, meshing with the gear wheel 32

upon the larger roller. A third gear 33 connects with a source of power.

In operation, the tube 35 is placed between the rollers 11 of the guides 10, and one edge of the tube is fed between the rollers 2 and 3 in such a manner that the axis of the tube, in plan view, is at an angle to the axes of the rollers. The tube 35 is of malleable metal, usually hot drawn, and of small diameter. Rolling down the walls of the tube enlarges it 60 to suitable dimension for fruit, or other, cans. The can with a seamless wall has numerous advantages, among which are the possibility of a more perfect seal at the ends, elimination of washers at the ends, and a greatly strengthened wall.

When fed at the proper angle, the tube is caught by the rollers and drawn in and the wall reduced in thickness. It is also enlarged. By passing the tube thru a succession of rollers it may be enlarged to the desired size. When the tube strikes the arm 26 of the stop 25, the sliding rod 22 is pushed back until the electric switch 24 is operated. Electric current then actuates the solenoid 20, and the 70 sliding core operating thru the bell cranks 13 and the drag rod 14, cause the reversing of the guides 10. As soon as the angle of the tube 35 is shifted to feed from the opposite side of the rollers, it feeds back out of the 75 machine, undergoing still further enlargement as it returns.

In dropping from the rollers the tube 80 strikes the lever 28. A vertical arm 27 is attached at right angles to lever 28. The arm 27 is pivoted at the center to the block 1 in such manner that when the lever 28 is forced down, the top half of arm 27 is forced forward. As it comes forward, it engages hook 23 and draws sliding rod 22 forward 85 until the electric contact of switch 24 is broken. The action of solenoid 20 is then halted. The coiled spring 15 then acts upon the drag rod and the guides 10 are brought back into their original position.

100 I claim:

1. A machine for the manufacture of seamless cans comprising rollers suitably mounted in bearings, an adjusting screw for regulating the pressure between said rollers, guides governing the angle at which the tube for the seamless wall of the can is fed between the rollers, and means for reversing the angle of the guides so that the tube will be fed back out of the machine.

110

2. A rolling machine comprising a main block having a longitudinal bore, a shaft within said bore one end of which acts as one of the machine rollers, a housing mounted upon the main block and hinged thereto at one end, a second shaft within said housing, a sleeve roller affixed to one end of said shaft, an adjusting means for regulating the amount of pressure between the rollers at the free ends of said shafts, consisting of bolts rising from said main block on either side of said housing, a crossbar between said bolts, and an adjusting screw working thru said crossbar; guides for directing a tube to said rollers at determined angle; means for changing the angle of said guides, consisting of vertical rods on either side of said rollers passing thru the main block, small rollers mounted upon said guides, bell cranks attached to the lower ends of said rods, a drag rod connecting the free ends of said bell cranks, a solenoid with a core connected with one of said bell cranks, and a spring with an action upon said drag rod counter to the action of said solenoid; a reversing means consisting of a slidable rod mounted at one edge of said main block having a hook at

one end, an electric contact at the other, and an adjustable stop between, and a lever, having a vertical arm and a horizontal arm mounted upon the side of said main block, the vertical arm of said lever impinging upon said hook and the horizontal arm swinging out beneath the ends of said rollers.

3. A machine for enlarging tubes comprising housings hinged together at one end, means for adjusting the distance between the loose ends, shafts within said housings, rollers at one end of said shafts, means for rotating said rollers upon each other, guides for directing a tube toward the rollers at a given angle, and means for automatically changing the angle of said guides with respect to said rollers.

4. A rolling machine having means for directing a tube toward rollers at a desired angle, means for reversing the angle after a determined amount of rolling, and means for again setting the directing means at the original angle as the tube leaves the machine.

In testimony whereof, I hereby affix my signature.

ARTHUR. W. SPAULDING.
